ATTORNEY

UNITED STATES PATENT OFFICE.

ALVAH M. GRIFFIN, OF KANSAS CITY, MISSOURI.

ACETYLENE-GAS GENERATOR.

1,311,270.

Specification of Letters Patent. Patented July 29, 1919.

Application filed July 10, 1918. Serial No. 244,198.

To all whom it may concern:

Be it known that I, ALVAH M. GRIFFIN, a citizen of the United States, residing at Kansas City, in the county of Jackson and State of Missouri, have invented certain new and useful Improvements in Acetylene-Gas Generators, of which the following is a specification.

This invention relates to acetylene gas generators, and has for its object to produce a machine of this character whereby the gas generated shall be maintained at substantially a uniform predetermined pressure until the supply of carbid is exhausted.

15 A further object is to produce an acetylene gas machine of the character set forth, which is of simple, strong, durable and inexpensive construction.

With these objects in view the invention consists in certain novel and useful features of construction and combinations of parts as hereinafter described and claimed; and in order that it may be fully understood reference is to be had to the accompanying drawing, in which:

Figure 1, is a central vertical section of an acetylene gas generator embodying the invention.

Fig. 2, is a horizontal section on the line 30 II—II of Fig. 1.

Fig. 3, is a fragmentary vertical section on the line III—III of Fig. 2.

In the said drawing 1 indicates a tank provided with a drain cock 2 and a removable lid 3, the lid being provided with a pressure gage 4, a relief valve 5 to reduce pressure by hand for light work, such for example, as required for operating a small torch, and a pop-off release 6 of any common and well-known type as conventionally illustrated, to operate for the release of excessive pressure.

To establish an air tight connection between the top of the tank and the lid a 45 rubber or equivalent gasket 7 is interposed between said elements, and clamping devices 8 are pivotally secured to the tank so as to be swung toward or from the lid preliminary to the removal of the latter or to placing the same in operative position. Arranged concentrically within the tank is an 50 annular cylindrical vessel 9, the outer wall of the same extending a considerable distance above its inner wall and being secured with a gas tight relation to the wall of the tank, the space between the inner

and outer walls of said vessel constituting a liquid seal.

10 is a magazine hopper fitting within and resting upon lugs 11 of the inner wall 60 of said vessel, but without bearing a gas tight relation thereto, so that gas generated in the tank may pass up through the passage of the said vessel to a point above the carbid hopper, the top of which stands 65 slightly above the top of the inner wall of said vessel, so that should water from the seal chamber overflow the inner wall of said vessel, it could not enter the carbid hopper but could flow down the exterior 70 side of the same and the inner side of the inner wall of the vessel.

The hopper is provided at its lower end or apex with a discharge opening and yieldingly closing said discharge opening is a 75 cone shaped valve 12. To hold the valve in position it is provided with a stem 13 extending up through the cover of the hopper and through a tube 14 depending from said cover. Within the tube the stem has a collar 15 engaged by the upper end of a coiled spring 16 bearing at its lower end against an internal supporting shoulder 17 of said tube, the arrangement being such that sufficient pressure upon the upper end of the 80 stem shall force the valve downward and permit carbid to drop from the hopper into the water with which the tank is charged to a suitable depth, this discharge of the carbid of course being instantly followed 85 by generation of gas, and in this connection it will be noted that the hopper is provided with a skirt 18 around its discharge opening to protect the valve from contact with water produced by overflow from the sealing chamber or by condensation on the exterior of the 90 carbid hopper.

19 is a by-pass connecting the interior of the tank above the water level thereof, to the interior of the said vessel above the water 100 level thereof, and said by-pass is controlled by a valve 20. A gas discharge pipe 21 extends from the upper part of the chamber of the tank, and to remove any foreign matter from the gas, said pipe terminates in a down 105 turned end 22 submerged in water contained in a cup 23, the cup having a filling L 24 below the level of pipe 21, so that sufficient water can not be poured into the cup to enter the tank. In the upper part of the cup is a 110 gauze or equivalent strainer 25 and above the strainer is a hair or equivalent packing 26.

The upper end of the cup is provided with a nipple 27 to which a hose is adapted to be connected for convenience in using the gas for welding or other purposes. The machine 5 is provided with a bell 28 fitting over the carbid hopper and depending into the water seal chamber.

To operate the generator immediately after the carbid hopper, the bell, and the lid 10 have been placed in position, the operator opens valve 20 to permit the gas to pass through the by-pass from the generating chamber of the tank to the vessel 9, closing the valve when the gage shows the requisite 15 pressure. The machine will stand in this condition until gas is drawn off through a hose or the like, the bell descending as the gas is consumed and the pressure on the interior of the bell thereby lessened, and applying downward pressure upon the valve 20 to open the same and supply additional carbid to the water in the tank and thus augment the supply and pressure of the gas therein sufficiently to reëlevate the bell and 25 permit the spring to reseat the valve.

In practice very little movement of the bell is required to open the valve or withdraw from engagement therewith. Consequently the pressure in the tank is kept substantially uniform and supplies gas at a substantially uniform pressure for welding and other purposes where it is desired to maintain a uniform pressure for a considerable period of time.

35 When it is necessary to recharge the hopper, the lid is unclamped and removed to permit the bell and then the hopper to be withdrawn from the tank.

When the carbid ash accumulates sufficiently, the tank can be drained by opening the stop cock 2.

A machine of the character described will be found very desirable, not only for welding, but for many other purposes, and can be 45 made in portable sizes and at comparatively small cost.

While I have described and shown the preferred embodiment of the invention it will be apparent that it is susceptible of 50 modification in minor particulars without departing from the principle of construction involved or sacrificing any of the advantages of the appended claims.

I claim:

55 1. An acetylene generator comprising a tank, means including a liquid seal chamber and a bell floating therein, dividing the tank into a generating chamber and a pressure chamber, a valve controlled by-pass connecting said chambers, and means actuated by descending movement of the bell for discharging carbid into the generating chamber.

60 2. An acetylene generator comprising a tank, relatively movable means dividing said

tank into a generating chamber and a pressure chamber, a valve controlled by-pass connecting said chambers, a hopper for discharging carbid into the generating chamber, a valve for the hopper to be automatically unseated when the pressure in the generating chamber falls below a predetermined point, and means for reseating the valve when the pressure in the generating chamber is restored to normal. 75

3. An acetylene generator comprising a tank, relatively movable means dividing said tank into a generating chamber and a pressure chamber, a valve controlled by-pass connecting said chambers, a hopper for discharging carbid into the generating chamber, a valve for the hopper to be automatically unseated when the pressure in the generating chamber falls below a predetermined point, means for reseating the valve 80 when the pressure in the generating chamber is restored to normal, and an automatic blow-off to operate when the pressure within the tank is excessive. 85

4. An acetylene generator comprising a tank, relatively movable means dividing said tank into a generating chamber and a pressure chamber, a valve controlled by-pass connecting said chambers, a hopper for discharging carbid into the generating chamber, a valve for the hopper to be automatically unseated when the pressure in the generating chamber falls below a predetermined point, means for reseating the valve when the pressure in the generating chamber is restored to normal, and a pressure gage, a manually operative pressure release valve, and an automatic blow-off for the tank. 95

5. An acetylene generator comprising a tank, means including a liquid seal chamber 105 and a bell floating therein, dividing the tank into a generating chamber and a pressure chamber, a valve controlled by-pass connecting said chambers, means actuated by descending movement of the bell for discharging carbid into the generating chamber, a discharge pipe for the generating chamber, having a down-turned outer end, a cup communicating with the lower end of said pipe, a liquid supply for the cup between the plane 110 of the upper part of the said discharge pipe and the end thereof within the cup, a filtration substance in the cup above the liquid level thereof, and a discharge nipple for the gas passing through said filtration substance. 115

6. An acetylene generator comprising a tank, a removable lid closing the tank with a gas-tight relation and provided with a pressure gage, manually-operable pressure 125 release valve and a gas blow-off, means including a water-seal and a gas bell partitioning the tank into a generating chamber and a pressure chamber, a valve controlled by-pass connecting said chambers, a hopper for 130

discharging carbid into the generating chamber, a spring-closed valve closing the discharge end of the hopper to be unseated by sufficient downward movement of the gas bell, and a gas discharge pipe for the generating chamber.

5 7. An acetylene generator comprising a tank, means including a liquid seal chamber and a bell floating therein, dividing the

tank into a generating chamber and a pressure chamber, means for generating gas in the generating chamber, means for introducing fluid under pressure in said pressure chamber, and means actuated by descending movement of the bell for discharging 10 carbid into the generating chamber.

In testimony whereof I affix my signature.

ALVAH M. GRIFFIN.
